UNIVERSAL SUPPORT FOR TYPEWRITER
PAPER

Alvin Z. Bailey, Yellow Springs, Ohio

Application March 11, 1949, Serial No. 80,983

7 Claims. (Cl. 197—133)

(Granted under the act of March 3, 1883, as
amended April 30, 1928; 370 O. G. 757)

1

The invention described herein, if patented, may be manufactured and used by or for the Government for governmental purposes, without the payment to me of any royalty thereon.

This invention relates to a container and support for typewriter paper of continuous form and has for one of its primary objects to provide such a device which may be detachably connected to the carriage of a typewriter.

Another object of the invention resides in the provision of a container support for typewriters which is so constructed as to be capable of mounting on the paper rest of all types of domestic typewriters.

Other objects and advantages of the invention will be apparent from the following description when taken in connection with the accompanying drawings, in which,

Figure 1 is an end elevational view of the holder and bracket applied to a typewriter, parts being shown in section;

Figure 2 is a plan view of the attachment, parts being broken away;

Figure 3 is a sectional view taken on the line 3—3 of Figure 2 and looking in the direction of the arrows; and

Figure 4 is a fragmentary end elevational view of the holder and bracket applied to a different design of typewriter.

When using more or less continuous sheets of paper in typewriters, it is highly desirable that some means be provided for supporting the main supply as the sheet is being fed around the platen, and it is also highly desirable that the holding means be supported on the carriage so that the sheet or web may be properly fed into the machine at all times. It is also important that the holder for the continuous web or sheet be adapted for mounting on various designs of typewriters so as to avoid the requirement for a multiplicity of such holders. The present invention comprises a container for the continuous web or sheet of paper to be fed to the platen, as well as a bracket so constructed as to be capable of application to any domestic typewriters now on the market.

The container of the present invention is indicated by the numeral 1 and is of box-like construction, adapted to receive a web of paper folded in zigzag form and capable of being discharged through the open top thereof. This container may be provided with one or more vertically extending slots 2 in its sides to permit observation of the amount of paper remaining in the container. The front wall of the container 1, that is, the wall adjacent to the typewriter is pro-

vided with keyhole slots 3, adapted to receive headed pins mounted on the bracket about to be described. This keyhole slot construction provides for the ready removal of the box or container 1, when the typewriter is being used for other purposes than typing on continuous sheets.

In the form of the invention shown in Figures 1, 2 and 3, the typewriter is indicated by the numeral 4 and the conventional paper rest thereof 5 is of rounded form as indicated by the numeral 5. The universal bracket construction which forms an important part of the present invention is indicated generally by the numeral 6, and includes a horizontal base or bridge member 7 extending longitudinally of the typewriter carriage and spanning the paper rest 5. A depending flange 8 may be formed at the rear of the base member 7, and extending downwardly and rearwardly from the lower edge of the flange 8, is an arcuate portion 9, having a radius of curvature corresponding substantially to that of the rear portion of the conventional paper rest 5. From the lower edge of the arcuate portion 9 of the bracket there extends a horizontal flange 10, which carries a vertically extending panel 11 provided with a pair of rearwardly extending headed pins 12, adapted to be received in the keyhole slots 3 of the container 1, so as to provide for the ready detachment of the container, as heretofore indicated.

The arcuate portion 9 of the bracket is provided with a pair of headed pins or plungers 13 extending through the arcuate portion 9 and provided with inner heads or nuts 14 for cooperation with keyhole slots 14' in the paper rest 5, and outer heads 15, adapted to be engaged by the finger of the operator. Springs 16 are interposed between the bracket portion 9 and the heads 15, so as to normally force the inner heads 14 into tight engagement with the inner surface of the paper rest 5, so as to securely hold the bracket in position and prevent rattling of the parts when the typewriter is being operated.

The forward longitudinal edge of the bridge or base member 7, is provided with a downwardly inclined portion 17, adapted to engage the paper rest of a different design of typewriter from that shown in Figure 1, and the downwardly inclined plain portion is provided with spring-pressed plungers identical with those just described and indicated generally by the numeral 18. In the disclosure of Figure 4, the typewriter is of a design provided with a downwardly inclined paper rest, as indicated by the numeral 19, and consequently the bracket 6 is positioned so that the

inclined portion 17 thereof engages flatly against the inclined portion of the paper rest, and the headed pins 18 are passed through keyhole slots in the paper rest and held against rattling by the springs 16, just as in the construction shown in Figure 1.

It thus appears that the novel bracket is readily adapted to both constructions of typewriters, that it supports the paper container on the typewriter carriage so that the paper may be properly fed to the platen, and that excess noise is avoided by reason of the spring-pressed plungers which maintain the parts tightly engaged at all times.

I claim:

1. A paper holder for typewriters comprising a container provided with one or more keyhole slots in a sidewall thereof, a bracket including a vertical portion and an inclined portion, one or more headed pins on the vertical portion of the bracket for cooperation with the keyhole slots, and means on the inclined portion of the bracket for securing the same to the paper rest of a typewriter.

2. A paper holder for typewriters comprising a container, a bracket connected to said container, and spring-pressed headed pins on the bracket for releasably securing the same to the paper rest of a typewriter.

3. A paper holder for typewriters comprising a container, a bracket including a vertical panel and an inclined portion, means for detachably connecting the container to the panel, and spring-pressed headed pins on the inclined portion for detachably connecting the bracket to the paper rest of a typewriter.

4. A bracket for supporting a paper container on a typewriter carriage, comprising a base member, a vertical panel on the base member adapted to be connected to the container, said base member including an arcuate portion adapted to engage the paper rest of one style of typewriter and an inclined portion for engaging the paper rest of another style of typewriter, and means on said arcuate portion and on said inclined portion for releasably securing the base member to either style of paper rest.

5. A bracket for supporting a paper container on a typewriter, comprising a base member, a

vertical panel on the base member adapted to be connected to the container, said base member including an arcuate portion adapted to engage the paper rest of one style of typewriter and an inclined portion for engaging the paper rest of another style of typewriter, and spring-pressed headed pins on said arcuate portion and on said inclined portion for releasably securing the base member to either style of paper rest.

10 6. A bracket for supporting a paper container on a typewriter carriage, comprising a base member, a vertical panel on the base member adapted to be detachably connected to the container, said base member comprising a horizontal portion adapted to extend longitudinally of the paper rest of a typewriter, an arcuate portion depending from one longitudinal edge of the horizontal portion, a downwardly inclined portion extending from the other longitudinal edge of the horizontal portion, and means on said arcuate portion and on said downwardly inclined portion for securing the bracket to the paper rest of different designs of typewriters.

20 7. A bracket for supporting a paper container on a typewriter carriage, comprising a base member, a vertical panel on the base member, adapted to be detachably connected to the container, said base member comprising a horizontal portion adapted to extend longitudinally of the paper rest of a typewriter, an arcuate portion depending from one longitudinal edge of the horizontal portion, a downwardly inclined portion extending from the other longitudinal edge of the horizontal portion, and spring-pressed headed pins on said arcuate portion and on said downwardly inclined portion for securing the bracket to the paper rest of different designs of typewriters.

ALVIN Z. BAILEY.
